UNITED STATES PATENT OFFICE

ALFRED MORRIS THOMSON, OF NEWARK, NEW JERSEY, ASSIGNOR TO DARDELET THREADLOCK CORPORATION, OF NEW YORK, N. Y., A CORPORATION OF DELAWARE

DESIGN FOR A ROD OR LIKE ARTICLE

Application filed July 24, 1930. Serial No. 36,456. Term of patent 14 years.

To all whom it may concern:

Be it known that I, ALFRED MORRIS THOMSON, a subject of the King of Great Britain, and resident of Newark, in the county of Essex and State of New Jersey, have invented a new, original, and ornamental Design for Rod or Like Article, of which the following is a specification, reference being had to the accompanying drawing, forming a part hereof.

In the drawing, Fig. 1 is a fragmentary side elevation of the rod broken away

through one of the cylindrical portions thereof;

Fig. 2 a fragmentary side elevation showing a portion of the rod on an enlarged scale; and

Fig. 3 a transverse sectional view taken on the line 3—3 of Fig. 2.

I claim:

The ornamental design for a rod or like article, as shown.

ALFRED MORRIS THOMSON.
